UNITED STATES PATENT OFFICE

MORTIMER C. ROSENFIELD, OF CLEVELAND, AND FRANK E. McCABE, OF CHAGRIN FALLS, OHIO, ASSIGNORS TO THE GRABLER MANUFACTURING COMPANY, OF CLEVELAND, OHIO, A CORPORATION OF OHIO

SIGN AND METHOD OF MANUFACTURING THE SAME

Application filed September 20, 1926. Serial No. 136,451.

This invention pertains to improvements in metal signs, especially of the sheet metal, vitreous enamel coated class, that are adapted for use as "safety zone" markers, 5 street signs, danger signals, advertising devices, bus or car stop signs, price signs, as for use about gasoline stations, and the like, the invention having to do also with the method of manufacturing the sign.

10 Signs of the class referred to are in very general use, and with respect to those of prior constructions which involve the vitreous enamel coated metal plates, it is the rule, rather than the exception, that after the signs have been in service a comparatively short 15 while the enamel becomes chipped about the edges of the signs or cracked by reason of the signs having been bent. It frequently happens, also, that the enamel becomes chipped 20 during the assembling of the parts whereof the completed sign is composed.

It is the primary purpose of our invention to provide a sign of the class referred to that is neat and attractive of appearance, and is 25 very substantial and durable, the same being stiffened and thoroughly protected about its edges by a rigid endless channel frame between the opposed flanges of which and the enamel coating of the sign there are preferably, fillers of compressible material.

Another object of the invention, as it pertains to the article, is the provision of a relatively simple construction of such a nature as will facilitate assembling of the parts and 35 greatly expedite and thus cheapen manufacture.

A further object is to provide a sign of the pedestal type wherein the pedestal is composed of separable sections to the end that 40 the same may be disjointed and packed, with the base and sign proper, in a minimum amount of space. This sectional construction also permits the pedestal to be varied in length by the use of a greater or less number 45 of sections, thereby to adjust the height of the sign.

With respect to the method of manufacture, our object is to provide one that will contribute to the ease and speed of forming 50 and assembling the parts, protect the enamel

coating of the sign during assembling, and facilitate the painting of the frame after the sign is mounted therein.

The foregoing objects with others herein-after appearing are attained in the embodiment of the invention illustrated in the accompanying drawing wherein Fig. 1 is a front elevation of a sign constructed in accordance with our invention; Fig. 2 is an enlarged vertical sectional view of the upper portion of the sign showing how the frame is attached to the pedestal; Fig. 3 is a perspective view of the constituents of the sign, proper, in separated condition; and Figs. 4, 5 and 6 are enlarged fragmentary sectional views showing the method of assembling the sign.

The device consists generally of the sign 1, a frame 2, a pedestal 3 that is made up of a plurality of separable sections, and a base 4. The sign 1 is of relatively heavy sheet metal that is coated on both sides with vitreous enamel. Suitable matter, depending upon the purpose to which the sign is to be put, is printed on one or both sides of the sign in accordance with usual practice. The frame 2 is formed of a strip of metal of suitable gauge, and in making the frame the ends of said strip are welded together so as to produce a cylindrical hoop or ring, as shown at the top 80 of Fig. 3. By means of suitable dies this hoop or ring is next given a form that is angular or substantially L-shaped in cross section, as illustrated in Fig. 4. The next step in the method of manufacturing the sign 85 is to place within this ring, successively, a ring 5 of compressible material, such as paper; the sign proper, designated 1; and a second ring 6, which is the same as ring 5. By a subsequent operation, and by means 90 of suitable dies, the ring is bent into the acute angular cross-sectional shape, as shown in Fig. 5. The third and final operation, performed by suitable pressure dies, imparts a channel formation to the ring, as most clearly 95 shown in Fig. 6, this operation completing the rigid, and permanently attached frame 2. The rings 5 and 6 protect the enamel coating of the sign from being cracked or chipped during the compression of the frame by re- 100

lieving it of undue strains or pressure. A further purpose of these rings will presently appear. The openings in the rings 5 and 6 permit a sufficient part of the sign to be observed therethrough as will enable the workman to place the sign upright in a cast metal fitting 7. After the frame is properly positioned within the fitting, the frame and the underlying portion of the sign, proper, are drilled in register with rivet holes in the side flanges of the fitting, and suitable fastening means, such as rivets, are then inserted through the registering holes of the various parts, and by these fastening means or rivets the parts are securely fastened together. The fitting 7 terminates at its lower end in a threaded stud 7^a which is adapted to be screwed into the upper end of the pedestal 3. The sections whereof the pedestal is composed may be connected together by internal nipples 8, and the lower section of the pedestal is screwed into the base 4. By using internal nipples, the joints between the sections of the pedestal are scarcely if at all noticeable. The reason for making the pedestal in sections is to facilitate packing for shipment, as well as to provide means for adjusting the height of the sign.

After the parts are assembled the frame and pedestal are painted, preferably by the spraying method, and the rings 5 and 6 serve their second purpose of protecting the sign from stray paint during this operation. After the paint is dry, the portions of the rings inwardly of the frame may be torn away, leaving only the margins of the rings between the peripheral portion of the sign 1 and the flanges of the frame 2.

It is clear from the foregoing that we have provided a device, and a method of manufacturing the same, which accomplish the objects of the invention as hereinbefore stated, and it is understood that the invention is not limited to the structural details herein recited further than is required by the terms of the appended claims.

Having thus described our invention, what we claim is:—

1. The herein described method of manufacture which consists in forming a frame of a strip of metal by connecting the ends of the strip together, placing within the frame a sign and layers of suitable material on opposite sides thereof, bending the strip to a form that is substantially U-shaped in cross section whereby it is caused to embrace the peripheries of the sign and said layers, painting the frame, and subsequently tearing away the said layers.

2. The herein described method of manufacture which consists in forming a frame of a strip of metal by connecting the ends of the strip together, bending the strip whereof the frame is constructed to a form that is substantially L-shaped in cross section, placing

within the frame a sign and layers of suitable material on opposite sides thereof, bending the strip to a form that is substantially U-shaped in cross section whereby it is caused to embrace the peripheries of the sign and said layers, painting the frame, and subsequently tearing away the portions of said layers inwardly of the frame.

3. The herein described method of manufacture which consists in forming a frame of a strip of a metal by connecting the ends of said strip together, placing within the frame a sign with layers of suitable material on opposite sides thereof, said layers being of such character that portions of the sign may be observed therethrough, bending the strip to a form that is substantially U-shaped in cross section whereby it is caused to embrace the peripheries of the sign and said layers, connecting the sign to a support in given relation with respect thereto, painting the frame, and removing the aforesaid layers.

4. The herein described method of manufacture which consists in forming a frame of a strip of a metal by connecting the ends of said strip together, bending the strip whereof the frame is constructed to a form that is substantially L-shaped in cross section, placing within the frame a sign with layers of suitable material on opposite sides thereof, said layers being of such character that portions of the sign may be observed therethrough, bending the strip to a form that is substantially U-shaped in cross section whereby it is caused to embrace the peripheries of the sign and said layers, connecting the sign to a support in given relation with respect thereto, painting the frame, and removing the portions of the aforesaid layers inwardly of the frame.

5. The herein described method of manufacture which consists in forming a cylindrical hoop of a strip of metal by welding the ends of the strip together, bending the strip whereof the hoop is constructed to a form that is substantially L-shaped in cross section, placing within the hoop a sign and paper rings disposed on opposite sides of the sign, subsequently bending the strip to a form that is substantially U-shaped in cross section whereby it is caused to embrace the peripheries of the sign and said paper ring, attaching the hoop to a fitting with the sign in given relation thereto, applying paint to the hoop, and subsequently tearing away the portions of the paper rings inwardly of the hoop.

6. The herein described method of manufacture which consists in forming a frame of a strip of metal by connecting the ends of said strip together, bending the strip whereof the frame is constructed to a form that is substantially L-shaped in cross section, placing a sign within the frame with layers of suitable material on opposite sides thereof, said layers being of such a character that a portion of

the sign may be observed therethrough, bending the strip to a form that is substantially U-shaped in cross section whereby the frame is caused to embrace the periphery of the sign and said layers, connecting the sign with a support in predetermined relation with respect thereto, applying paint to said frame and removing the portions of the aforesaid layers within said frame so as to expose the inner portion of the sign.

7. A device of the character described comprising a sign consisting of a channel shaped frame member bent into the form of a cylindrical hoop and permanently embracing the periphery of the sign, a fitting embracing the abutting ends of said channel member and terminating at its lower end in a stud adapted to be secured to the upper end of a pedestal and fastening devices extending through the fitting, frame and the peripheral portion of the sign.

8. A device of the character described comprising a pedestal, a sign adapted to be supported on said pedestal and comprising a channel member embracing the sign and bent into the form of a loop with its opposite ends abutting, a fitting embracing the abutting ends of said channel member and terminating at its lower end in a threaded stud adapted to be threadedly secured to said pedestal and fastening devices extending through registering apertures in the fitting, frame and sign.

9. A device of the character described comprising a sign consisting of a channel shaped frame member bent to permanently embrace the periphery of the sign, a fitting embracing the abutting ends of said channel member and terminating at its lower end in a stud adapted to be secured to the upper end of a pedestal and fastening devices extending through the fitting, frame and the peripheral portion of the sign.

In testimony whereof, we hereunto affix our signatures.

45 MORTIMER C. ROSENFIELD.
